UNITED STATES PATENT OFFICE.

JACOB A. STARRETT AND EDWIN F. WELSH, OF WILMERDING, PENNSYLVANIA, ASSIGNORS OF ONE-TWENTIETH TO WILLIAM F. WOOD, OF SAME PLACE.

LIFTING-JACK.

SPECIFICATION forming part of Letters Patent No. 599,536, dated February 22, 1898.

Application filed October 5, 1897. Serial No. 654,156. (No model.)

To all whom it may concern:

Be it known that we, JACOB A. STARRETT and EDWIN F. WELSH, citizens of the United States, residing at Wilmerding, in the county 5 of Allegheny, State of Pennsylvania, have invented certain new and useful Improvements in Lifting-Jacks, of which the following is a specification, reference being had therein to the accompanying drawings.

10 This invention relates to lifting-jacks, and is particularly adapted for all classes of work in which devices of this character are employed, as well as for use in connection with oil-well machinery for the purpose of manipulating the tools used in such work.

15 It has for its object to provide a novel means for communicating power from the operating-lever to the lifting-bar and for retaining said bar in its elevated position when the operating-lever is moved to obtain an additional elevation of the bar.

20 It has for a further object to provide an improved form of tripping device for the purpose of releasing the retaining mechanism when it 25 is desired to lower the lifting-bar.

25 Other objects and advantages of the invention will hereinafter appear in the following description, and the novel features thereof will be particularly pointed out in the appended claims.

30 In the accompanying drawings, Figure 1 is a vertical section through the invention. Fig. 2 is a vertical section on the line 2 2 of Fig. 1, looking in the direction of the arrow. Fig. 3 is a detail perspective of the tripping device. Fig. 4 is a similar view of the cam-lever. Fig. 5 is a detail of the clutch-block, and Fig. 6 is a plan of the lifting mechanism assembled.

35 Like letters of reference indicate like parts throughout the several figures of the drawings.

40 The letter A designates a standard provided with a suitable base A' and at its upper portion with parallel segmental extensions A².

45 The upper portion of the standard is provided with an enlarged recess A³ for the reception of the lifting, retaining, and tripping mechanism and with inwardly-turned walls a at its upper portion to guide the lifting-bar B, 50 which slides therein. The lower portion of said bar is provided with a foot B', which is

adapted to engage the article to be lifted, as is usual with this class of devices, and its upper end is provided with a head B² for a similar purpose. The bar is smooth throughout 55 its length and fits between the walls of the standard, so as to slide therein without friction.

For the purpose of lifting the bar an operating-lever C is provided, which is forked at 60 its inner end, as at C', and pivoted to the segmental extensions A² by any suitable means—for instance, a bolt or pintle C². Journaled upon the inner end of this lever are oppositely-located links D by means of the cross-bar D², carried by the forked ends of the lever C. The links are spaced apart and held in their relative positions by means of a sleeve D². Embracing the lifting-bar is a strap E, formed in two parts E' and secured 70 together by means of a bolt e. The projecting ends of the portions E' of the strap are provided with apertures to receive the pintles F' of a cam-lever F, the outer end of said lever being pivotally connected with the lower 75 ends of the strap D by means of a journaling-pin F². The cam-lever F is provided with a face or seat portion f, which extends at an angle to the pivots F', so that when the cam-lever is rotated it will bear against a clutch-block G, 80 which is located between the lever and the lifting-bar to hold the lever in position. This block is provided with a roughened or serrated face G' and at its rear with a recess G², within which the end of the lever operates 85 and against the wall of which it bears. By this structure it will be seen that when the end of the operating-lever is depressed motion will be communicated through the links D to the cam-lever F, so that the same will 90 be thrown into contact with the clutch-block and thus clutch the lifting-bar and lift the same in the upward movement of the inner end of the operating-lever.

The means for retaining the lifting-bar in its elevated position consists of a strap E², clutch-block G², and cam-lever F² similar to those just described, with the exception that the outer end of the cam-lever is not pivoted to any movable part, but rests upon a stop H. 100 Extending downward from the upper portion a of the standard upon opposite sides of the

lifting-bar are pins H' , about which are located coil-springs H^2 , which bear upon the upper surface of the strap E^2 , and thus normally force the same downward so as to engage the outer end of the cam-lever with the stop H , and thus move the lever so as to bring the clutch-block into contact with the lifting-bar. These springs and pins just described may be omitted and any other desirable form 10 of spring used in their stead. It is obvious that the upward movement of the lifting-bar will carry this retaining device slightly upward with it and then pass freely through the same, while the downward movement of 15 the bar will bring the cam-lever into contact with the stop H and thus clutch and hold the bar against further downward movement.

When it is desired to release the retaining device from the bar in order to permit the same 20 to be lowered, a tripping-lever is used, such as is shown in detail in Fig. 3, which consists of a horizontal portion I , journaled in the standard and provided at one end with an operating-handle I' . Upon opposite sides of the 25 lifting-bar the tripping device is provided with an arm I^2 , having upwardly-extending pins I^3 , between which and the lower side of the strap E^2 are located springs I^4 , which are of greater tension or strength than the spring 30 H^2 , heretofore described. The bar I is provided with a lug I^5 , which is adapted to seat itself in a recess I^6 , formed in the standard, when the lug and recess come into alignment with each other. This lug is normally held 35 into contact with the side of the standard by means of a spring I^7 , located between the head I^8 on the tripping device and one wall of the standard. From this description it will be seen that when the tripping device 40 stands in the position shown in Fig. 1 the springs I^4 are out of action, as their tension is less than the springs H^2 . If the handle of the tripping device be turned at this time, so as to bring the lug I^5 into the recess I^6 , the 45 springs I^4 would be compressed, and being of greater tension than the springs H^2 when the weight of the lifting-bar is released will compress the springs H^2 , and thus release the clutch-block G , which retains the lifting-bar. 50 This action of the parts will occur when the operating-lever is depressed so as to remove the weight from the retaining device and support it upon the clutch-block connected with the lifting-lever. When the weight is so supported, the tripping device will release the retaining-clutch, and the lifting-bar may be lowered by gradual movement of the operating-lever, which at this time is clutched to the 55 bar, or, if preferred, by throwing the outer end of the lever upward the bar will be dropped at once to its lowest position. The 60 operation of the several parts has been fully described, and their relations to one another in the operation of the lifting-jack as a whole 65 will be clearly understood from the foregoing description.

It is obvious that changes may be made in

the specific details of construction of the several parts of the invention without departing from the spirit of the same as defined by the 70 appended claims. For instance, the base or lower portion of the lifting-jack may be dispensed with below the line xx in Fig. 1 of the drawings and the lifting, retaining, and tripping mechanisms mounted in any suitable manner to adapt them to different classes of work.

Having described our invention and set forth its merits, what we claim as new, and desire to secure by Letters Patent, is— 80

1. In a lifting-jack, the combination with a lifting-bar and its support, an operating-lever, a clutch-block adapted to engage said bar, a cam-lever operating against said clutch-block, and connections between said cam-lever and operating-lever, of a retaining-strap, a cam-lever pivotally mounted therein and bearing at its power end against a stationary member of the support, a clutch-block located between said cam-lever and lifting-bar, and a spring extending from said strap to said support to normally force the strap downward; substantially as specified. 85

2. In a lifting-jack, the combination with a lifting-bar and its support, of a retaining-strap, a cam-lever pivotally mounted in said strap and bearing at the power end against a stationary member of the support, a clutch-block located between said cam-lever and lifting-bar, and spring means to normally 90 force said strap downward, substantially as specified. 95

3. In a lifting-jack, the combination with a lifting-bar and its support, of a retaining-strap, a cam-lever pivotally mounted in said 105 strap and bearing at one side against a stationary member of the support, a clutch-block located between said cam-lever and lifting-bar, and a spring located between the upper end of said strap and the support for the bar, 110 substantially as specified.

4. In a lifting-jack, the combination with a lifting-bar and its support, of a retaining-strap, a cam-lever pivotally mounted in said 115 strap and bearing at one end against a stationary member of the support, a clutch-block located between said cam-lever and lifting-bar, a spring located beneath said strap, and means for increasing and releasing the tension of said spring, substantially as specified. 120

5. In a lifting-jack, the combination with a lifting-bar and its support, of a retaining-strap, a cam-lever pivotally mounted in said 125 strap and bearing at one end against a stationary member of the support, a clutch-block located between said cam-lever and lifting-bar, a spring located beneath said strap, and a pivoted arm upon which said spring is supported, substantially as specified.

6. In a lifting-jack, the combination with a lifting-bar and its support, of a retaining-strap, a cam-lever pivotally mounted in said 130 strap and bearing at one end against a stationary member of the support, a clutch-block

located between said cam-lever and lifting-bar, a spring located beneath said strap, a pivoted arm upon which said spring is supported, and means for retaining said arm in position to hold said spring under tension, substantially as specified.

7. In a lifting-jack, the combination with a lifting-bar and its support, of a retaining-strap, a cam-lever pivotally mounted in said strap and bearing at one end against a stationary member of the support, a clutch-block located between said cam-lever and lifting-bar, a spring located between the upper end of said strap and the support for the bar, a spring beneath said strap, and means for placing and holding said spring under tension, substantially as specified.

8. A lifting-jack comprising a lifting-bar, an operating-lever, a cam-lever pivotally connected therewith and adapted to elevate said bar, a retaining device adapted to operate in the downward movement of said bar to retain the same in its elevated position, a tripping device for releasing said retaining device to permit the downward movement of the bar, and a supporting-spring interposed between said tripping and retaining devices, substantially as specified.

9. A lifting-jack comprising a lifting-bar, a support therefor having oppositely-located extensions, an operating-bar pivoted between said extensions, a strap surrounding said bar,

a cam-lever adapted to clutch said bar and pivotally connected to the operating-lever, a retaining-strap, a cam-lever pivoted therein to clutch said bar, a stationary support beneath the free end of said lever, and a spring bearing upon the upper surface of said retaining-strap to normally force the same downward, substantially as specified.

10. A lifting-jack comprising a lifting-bar, a support therefor having oppositely-located extensions, an operating-bar pivoted between said extensions, a strap surrounding said bar, a cam-lever adapted to clutch said bar and pivotally connected to the operating-lever, a retaining-strap, a cam-lever pivoted therein to clutch said bar, a stationary support beneath the free end of said lever, a pivotally-mounted tripping device adapted to operate beneath said retaining device to elevate the same and release the clutch upon the bar, and springs interposed between said support and retaining device and between said retaining and tripping devices, substantially as specified.

In testimony whereof we affix our signatures in presence of two witnesses.
